(57) **CLAIM**

The ornamental design for a pet harness as shown and described.

DESCRIPTION

FIG. 1 is a perspective view of a pet harness showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof;

The broken lines showing of a buckle and D-rings shown in FIGS. 1-7 represent portions of the pet harness that form no part of the claim. The remaining broken lines shown in the drawings depict stitching on the pet harness that form no part of the claimed design.
